UNITED STATES PATENT OFFICE.

RALPH GRACE, OF BATTLECREEK, MICHIGAN, ASSIGNOR TO SIMON A. KOHN, OF CHICAGO, ILLINOIS.

TOASTING-OVEN.

SPECIFICATION forming part of Letters Patent No. 784,854, dated March 14, 1905.

Application filed July 9, 1902. Serial No. 114,854.

To all whom it may concern:

Be it known that I, RALPH GRACE, of Battle-creek, in the county of Calhoun and State of Michigan, have invented certain new and useful Improvements in Toasting-Ovens; and I do hereby declare that the following is a full, clear, and exact description thereof, reference being had to the accompanying drawings, and to the letters of reference marked thereon, which form a part of this specification.

This invention relates to improvements in toasting and broiling devices and apparatus, and refers to an apparatus designed for toasting cereals and like food products, and also to a novel heating device adapted to be employed as the toaster in the apparatus shown and also employed generally for toasting or broiling food products.

In the drawings, Figure 1 is a longitudinal section taken through a toasting-oven made in accordance with my invention. Fig. 2 is a transverse section taken on line 2 2 of Fig. 1. Fig. 3 is a side elevation of one end of the oven. Fig. 4 is an enlarged fragmentary vertical section of one of the toasters, taken on line 4 4 of Fig. 1. Fig. 5 is a fragmentary bottom plan view of one of the lower toasters, taken on line 5 5 of Fig. 1.

In said drawings, A designates in a general way the elongated outer casing or inclosure of a toasting-oven, which may be made of heavy sheet metal of a gage to give rigidity thereto and supported on a skeleton frame consisting of horizontal and vertical bars a a' in the manner shown. The oven is supported on vertical legs or standards A', suitably connected with the skeleton frame of the oven. Said casing preferably surrounds and incloses all of the principal operative parts of the apparatus.

B designates an endless traveling belt or carrier, which is trained about horizontal rollers B' B' B² B² at the front and rear ends of the oven, respectively. The shafts b of the rollers B' B' extend outside of the oven and are rotatively mounted in bearing-brackets a^2 a^2 , attached to the corner-posts a' of the skeleton frame. The shaft b of one of the rollers B' is herein shown as extended beyond its bear-

ing and is provided with a pulley B³, through which power is applied to rotate said rollers 50 through the medium of a belt B⁴ and to impart therethrough movement to the belt. The belt is of a foraminated nature, being preferably made of woven wire. Said pairs of rollers B' B' and B² B², respectively, are located at each end of the oven, one over the other, and the upper and lower laps of the belt (upon the former of which the material to be toasted is carried) travel through the oven in horizontal planes. The shafts of one 60 of the pairs of rollers (the rollers B', as herein shown) are mounted in horizontally-movable blocks b^2 , Fig. 3, in the bearings a^2 , whereby the rollers B' may be moved toward and from the rollers B² to maintain the belt 65 in proper tension. The movement of said bearing-blocks b^2 are controlled by screw-shafts b^3 , which are connected with the boxes and have screw-threaded engagement with the brackets a^2 . The upper lap of the belt B is 70 supported intermediate the pulleys B' B² by means of horizontal rollers B⁵, which extend transversely through the oven beneath the upper lap of the belt and are rotatively mounted in bearings B⁶, Fig. 3, outside of the oven 75 and attached to the vertical members a' of the frame. The material is fed to the rear end of the upper lap of the belt through the medium of a chute C, Fig. 1, communicating with a hopper C', to which the cereal to be 80 toasted is delivered, and said chute is provided with a valve or gate C', by which the feed of the cereal to the belt is regulated. The toasted material is discharged from the belt at the front end of the oven through the 85 medium of an inclined discharge-spout D, which is located with its inner end closely adjacent to the vertical portion of the belt near the lower roller B', and said chute extends outside of the casing, so as to deliver the 90 toasted material to the exterior thereof.

E designates a plurality of toasters or heaters located above the upper lap of the carrier-belt B, and E' E' a plurality of similar toasters or heaters located between the upper and lower laps of said belt. The heat of

- the upper and lower toasters is directed toward the upper and lower sides of the upper lap of the belt, and said toasters are made of a width approximately to the width of the belt. Said toasters, as herein shown, are heated by gas, and each of said toasters is provided at its side remote from the upper lap of the belt with a gas-chamber c , Fig. 4, into which the gas is delivered by means of a flexible pipe F , leading through the wall of the oven and connected with said gas-chamber. The gas-pipes F are connected outside of the oven with supply-pipes F' , supported on brackets F'' , attached to the side wall of the oven in the manner shown in Fig. 3. Valves f are located between the supply and branch pipes to control the supply of gas to the toasters. Said flexible pipes F are coated with asbestos or like heat-insulating material.
- 15 In lieu of said chamber a continuous coil of burner-pipes may be provided, if desired. Each gas-chamber c is provided with a plurality of gas jets or burners e' , directed toward the upper lap of the belt. Located in front of the gas-burners of each toaster—to wit, below the burners above the belt and above the burners below the belt—is a foraminated heat-radiating member E'' , herein shown as made of fine wire gauze or screen, which is attached at its outer margin to a frame e' , connected with the gas-chamber c in any suitable manner. It is intended that the flames from the burner-jets e' shall not pass through the said screen, but shall heat the screen to a high temperature, the heat being thrown out or radiated from the said screens to the material on the belt. In this manner direct contact of the flames with the material being toasted is avoided, and consequent burning thereof is prevented.
- 20 The upper toasters E are supported through the medium of vertical bars G G' , which extend upwardly through the top wall of the oven-casing and are attached at their lower ends to divergent supports $G' G'$, (preferably of a flexible nature, such as chains.) Said supports $G' G'$ are connected with the toasters at their lower ends between the sides and centers thereof, as shown in Fig. 2, whereby said toasters are held in balance and are loosely connected with the centrally-located bars G G' . The lower toasters are supported on the upper ends of vertical bars H , which extend upwardly through the lower wall of the oven-casing. The bars H for each toaster are located one on each side of the lower lap of the belt and are connected with diagonally opposite corners of the toasters. As herein shown, each of the toasters is provided at its sides with transverse shafts H' , each of which is rigid with one of the adjacent bars H . Said shafts H' extend from one end of the toaster to the other and are loosely mounted in bearings h , attached to the under side of the toaster, thereby providing a wide bearing for each of

the shafts on its associated toaster in a manner to hold the toaster horizontal. Said toasters E E' are adapted to be moved toward and from the upper lap of the belt, as indicated in dotted lines in Fig. 1 at the right-hand side of 70 said figure, and said toasters are also adapted to be tilted to change the angles thereof with respect to the horizontal plane of the belt, as indicated in the left-hand side of Fig. 1 in dotted lines. For these purposes the said bars G and 75 H are provided on their margins with teeth g and h' , constituting racks which are adapted for engagement with gear-wheels I I' , which are affixed to horizontal shafts $I^2 I^3$, located above and below the oven-casing, respectively. The 80 gear-wheels I of the upper shafts are located centrally of their shafts to engage the centrally-located supporting-bars G of the upper toasters, while the gear-wheels I' of the lower shafts are located near the ends of their shafts 85 to engage the bars H , which are located at the sides of the toasters. Said upper shafts are mounted in bearings i , attached to the upper frame members of the oven at the top corners thereof, while the lower shafts engage similar bearings i' , attached to the lower frame members a . Said racks also engage at the sides thereof remote from the gear-wheels 90 vertical guides $i^2 i^3$, adapted to hold the racks in mesh with the gear-wheels. The said 95 shafts are provided outside of their bearings with cranks $i^4 i^5$, whereby the same may be rotated to raise or lower the toasters, and said shafts are provided near said cranks with ratchet-wheels i^6 , adapted for engagement by 100 clicks i^7 , pivoted on the bearings $i^8 i^9$ at the outer end of said shaft, whereby said toasters may be locked in any desired vertical position. The shafts $i^2 i^3$ of each pair controlling the movement of one toaster are independently 105 movable with respect to each other, so that when it is desired to change the angle of the toaster with respect to the horizontal plane of the belt one of said rack-bars is moved upwardly or downwardly farther than the 110 other, as indicated in dotted lines at the left-hand side of Fig. 1, whereby the end of the toaster to which said elevated or lowered rack-bar is attached is raised or lowered with respect to the opposite end thereof. The rack-bars may and will desirably be in practice 115 provided with graduation-marks, which may be read from the upper and lower ends of the guides $i^2 i^3$, whereby the positions of the toasters with respect to the belt may be readily 120 determined from the exterior of the oven. The oven is provided at one end thereof with a flue or chimney A^2 , through which the heated gases may escape from said oven. The oven is also provided at one or more 125 points with air-inlet openings A^8 , Fig. 1, controlled by dampers, whereby air may be supplied to the interior of the furnace to support combustion of the gas heating the toasters. The side walls of the oven are also pro- 130

vided near the level of the upper lap of the belt with windows A', which are closed with glass or other transparent material and through which the operation of the toasters 5 may be observed. Said oven in the practical construction thereof will also be provided with oven-doors, (not shown,) whereby access may be afforded to the interior of the oven for the purpose of cleaning or repairing the 10 interior parts thereof.

The belt may be made to travel at as slow or high rate of speed as desired, increasing the speed of the driving mechanism. Moreover, by reason of the adjustment of the 15 toasters with respect to the upper lap of the belt, whereby said toasters may be moved toward and from the belt or adjusted at an angle thereto, I am enabled to variously apply the heat of the toasters in different parts 20 of the travel of the belt through the oven, and thereby accurately regulate the amount of heat directed upon the cereal from any one of the toasters. For instance, it may be desirable in toasting certain cereals to apply a relatively low heat to the incoming cereal and to gradually increase the heat as the cereal 25 passes through the furnace. This I am enabled to accomplish by moving the forward toaster or toasters farther from the belt than the rear toaster or toasters, thereby gradually 30 decreasing the distance between the succeeding toasters and the belt as the material is carried forwardly through the oven. Moreover, certain kinds of cereals require less heat 35 to toast the same than others, and in this event all of said toasters may be removed a distance away from the belt suitable to such cereal. This result may be readily accomplished by the mechanism provided therefor. If desired, 40 but one set of heaters may be employed, and said set may be located either above or below the upper lap of the belt. I prefer to employ the two sets, as herein shown, as I am thereby enabled to more uniformly apply the heat 45 to the material being toasted. Moreover, so far as the broader aspect of my invention is concerned I may apply a single toaster made of a size to correspond with the conditions.

The heating devices E E' have been herein 50 designated as "toasters" and in the construction shown are properly so designated. It will be observed that heating devices made as described may be employed in other relations for toasting, broiling, or otherwise cooking 55 food products—as, for instance, the heaters may be used for broiling meats.

An important feature of the construction 60 of the heating device is the provision of the foraminated-radiating element located in front of the burners of each device. Said foraminated radiating element prevents the flames of the burners impinging directly upon the material being toasted or otherwise cooked and prevents scorching or irregular cooking 65 or toasting of the food product. As before

stated, the flames heat the foraminated element to a high temperature, and the heat is diffused or radiated thereby on all parts of the food product alike, whereby said product is uniformly toasted or broiled. In the use 70 of the heating devices for broiling meats the uniform heating of the surface of the meat serves to produce on the surface of the meat early in the broiling process a scaling crust which prevents the escape of the nutrition 75 juices of the meat. If the flames impinge directly upon the meat being broiled, the heating effect is irregular, and as a consequence the meat is heated sufficiently to cause the juices to flow before the surface scaling of the 80 meat is effected. This feature of the construction of the heaters is also important when applied as toasters, as it prevents irregular toasting of the food product being treated.

It is obvious that changes may be made in 85 the structural details of the illustrated embodiment of the invention without departing from the spirit of my invention, and I do not wish to be limited to such details except as hereinafter made the subject of specific claims. 90

I claim as my invention—

1. A toasting-oven comprising an endless, traveling belt upon the upper lap of which the material to be toasted is carried through the oven, a flat, horizontal toaster arranged above 95 and closely adjacent to said upper lap of the belt and having a plurality of burners which direct their flames toward said belt, a flame-retaining, heat-radiating, foraminated sheet located between the burners of said toaster and 100 the belt, and means for supplying a burning fuel to said toaster.

2. A toasting-oven comprising an endless, traveling foraminated belt upon the upper lap of which the material to be toasted is carried 105 through the oven, flat, horizontal, gas-heated toasters arranged above and below and closely adjacent to the upper lap of said belt and provided with burners which direct their flames toward said upper lap of the belt, flame-re- 110 taining, heat-radiating, foraminated sheets located between the burners of said toasters and the belt, and means for supplying a burning gas to said toasters.

3. A toasting-oven comprising an endless, 115 traveling belt upon the upper lap of which the material to be toasted is carried through the oven, a flat, horizontal toaster arranged above and closely adjacent to said upper lap of the belt and having a plurality of burners which 120 direct their flames toward said belt, a flame-retaining, heat-radiating, foraminated sheet located between the burners of said toaster and the belt, means for supplying a burning fuel to said toaster, and means for varying the 125 heat applied to the material by said toaster.

4. A toasting-oven comprising an endless traveling belt upon the upper lap of which the material to be toasted is carried through the oven, a flat, horizontal toaster arranged above 130

- and closely adjacent to said upper lap of the belt and having a plurality of burners which direct their flames toward said belt, a flame-retaining, heat-radiating, foraminated sheet 5 located between the burners of said toaster and the belt, means for supplying a burning fuel to said toaster, and means for moving said toaster toward and away from the upper lap of the belt.
- 10 5. A toasting-oven comprising an endless traveling belt upon the upper lap of which the material to be toasted is carried through the oven, a plurality of flat, horizontal, gas-heated toasters arranged above and closely adjacent 15 to said upper lap of the belt and provided with burners which direct their flames toward said upper lap of the belt, means for separately moving said toasters toward and away from the belt, and means for supplying a burning 20 gas to said toasters.
6. A toasting-oven provided with an endless, traveling, foraminated belt, upon the upper lap of which the material to be toasted is carried through the oven, a plurality of toasters arranged above and below said upper lap 25 of the belt, means for separately raising and lowering said toasters with respect to the belt, and means for separately tilting the toasters
- to vary the angles thereof with respect to the belt. 7. A toasting-oven provided with an endless, traveling belt upon the upper lap of which the material to be toasted is carried through the oven, a toaster arranged to direct the heat thereof upon the material carried on the belt 30 and means for moving the toaster toward and away from the belt comprising rack-bars connected at their inner ends with the toaster, 35 rotative shafts provided with gear-pinions which mesh with the rack-bars, and means for locking 40 said shafts from rotation.
8. A toasting-oven provided with an endless, traveling, horizontal belt upon the upper lap of which the material to be toasted is carried through the oven, a toaster for heating 45 the material on said belt, and means for tilting the toaster to vary the angle thereof with respect to the belt.

In testimony that I claim the foregoing as my invention I affix my signature, in presence 50 of two witnesses, this 24th day of June, A. D. 1902.

RALPH GRACE.
